UNITED STATES PATENT OFFICE.

AUGUST M. BECKER, OF CLIFFSIDE, NEW JERSEY, ASSIGNOR TO FRANK A. BECKER,
OF CLIFFSIDE, NEW JERSEY.

PICTURE-EXHIBITOR.

1,057,993.

Specification of Letters Patent.

Patented Apr. 1, 1913.

Continuation of application Serial No. 487,432, filed April 2, 1909. This application filed October 19, 1912.
Serial No. 726,729.

To all whom it may concern:

Be it known that I, AUGUST M. BECKER, a citizen of the United States of America, residing at Cliffside, county of Hudson, 5 State of New Jersey, have invented certain new and useful Improvements in Picture-Exhibitors, of which the following is a specification.

This invention relates to certain improvements in picture-exhibitors of that class in which a plurality of picture-exhibiting frames are arranged in a casing and engaged by means of bent lever-arms which engage one frame after the other and lift it 10 over the top of the casing to the upper front-part of the same and retain it in this position until the next following exhibiting frame tilts it over, exhibiting the rear-part of the picture-exhibiting frame at the front- 15 part of the casing, to be then returned along inclined ways at the interior of the casing to the rear-part of the same in such a manner that the swinging of the individual picture-frames over the casing into elevated 20 position in front of the same and back into tilted or return-position is accomplished in a very reliable manner and by a simple operating mechanism; and for this purpose the invention consists of a picture-exhibitor 25 which comprises a casing open at the front and rear, a plurality of exhibiting frames in which pictures are placed both at their front and rear, inclined ways at the upper part of the casing for carrying the frames 30 in backward direction, lever-arms by which they are engaged and lifted over the top of the casing to the upper front-part of the same, means for retaining the frames at the upper front-part for exhibition and means 35 for tilting the same in downward direction by the next succeeding exhibiting-frame so as to be returned to and along the ways to the rear-part of the casing.

The invention consists further of the arrangement of a casing provided with a hinged and spring-actuated rear-wall provided with upwardly and outwardly-bent lugs near its upper corners which are engaged by the operating lever-arms for 40 swinging back the rear-wall and permitting engagement with the ears of the rearmost picture-frame; and the invention consists lastly of certain details of construction 45

which will be fully described hereinafter and finally pointed out in the claims.

In the accompanying drawings, Figure 1 represents a perspective view of my improved picture-exhibitor, shown in closed position, Fig. 2 is a perspective view of the same, showing the hinged front-wall or 50 cover in open position and one of the picture-exhibiting frames in position at the upper front-part of the casing, Fig. 3 is a detail view of one of the picture-exhibiting frames, detached from the casing, Fig. 4 is 55 a vertical transverse section of the exhibitor, taken on line 4, 4, Fig. 2, Fig. 5 is a vertical longitudinal section of the operating mechanism of the picture-exhibitor on line 5, 5, Fig. 4, drawn on a larger scale, and Fig. 6 60 is a rear-elevation of the upper part of the exhibitor, also drawn on a larger scale.

Similar letters of reference indicate corresponding parts throughout the several figures of the drawings.

Referring to the drawings, *a* represents the casing of my improved picture-exhibitor, which consists of a base *a*¹, two upright side-walls *a*² and a rounded-off top *a*³. The side-walls *a*² of the casing *a* are provided 75 at their upper interior parts with ways *b* which are inclined from the front toward the rear, and which are preferably made of stout sheet-metal strips or other suitable material, said ways serving for returning the 80 picture-exhibiting frames *f*, which are provided with U-shaped wire-ears *f*¹ attached to their upper corners, from the forward-end of the casing toward the rear-end of the same. The front-ends of the inclined ways 85 *b* are provided with upwardly-bent guide-arms *b*¹ which are provided with ball-shaped ends *b*² and with notches *b*³ at their inner edges. The guide-arms *b*¹ serve to take up the ears *f*¹ of the picture-exhibiting frames 90 *f* so as to guide them onto the inclined ways *b*. The rear-ends of the inclined ways are provided with upwardly-bent stops *b*⁴ which serve to arrest the ears of the picture-frames 95 *f* when they arrive at their rearmost position.

In suitable bearings in the upper parts of the side-walls *a*² of the casing *a* are supported lever-arms *d*, which are bent inwardly at their rear-ends and provided with fixed hooks *d*¹ which serve to engage the wire-ears of the picture-frames *f* and lift them 100 105

away from the rear-stops b^4 of the inclined guideways b . The inner ends of the lever-arms d are connected by a transverse rod d^2 so that both lever-arms d are operated together. One of the lever-arms d is provided on its outer part with a button d^3 by which the lever-arm is taken hold of for moving it backward so as to take hold of the rear-most picture-frame in the casing and then forward so as to bring it over the top into inclined position on the front-arms, as shown in Fig. 4.

To the front-part of the casing is applied a lid g , which is hinged to the base of the casing and provided with a hinged catch g^1 , having an opening, at its upper end for engaging a stud g^2 on the front-part of the casing when the exhibitor is not in use.

To the lower rear-part of the base a^1 is hinged a rear-wall or cover h which is provided at its upper part with inwardly and outwardly-bent lugs h^1 that are engaged by the lever-arms d when they are swung into their rearmost position. The lower part of the hinged rear-cover h is connected by a strong spring h^2 with a fixed point on the bottom of the casing so as to draw the rear-cover inwardly and hold the same in closed position. When the lever-arms are moved in backward position so as to engage the ears of a picture-exhibiting frame, they press on the outwardly-curved lugs h^1 and move the rear-cover back against the tension of its spring so as to enter between the side walls and rear-cover. The lever-arms are then moved into downward position until they arrive in recesses h^3 of the side-walls. In this position, the hook-shaped ends of the lever arms d engage the ears of the rear-most picture-frame f which is then lifted away from the guide-ways b over the rear-stops b^4 of the same by the upward and forward motion of the lever arms, and moved over the rounded-off top-part of the casing, the picture-frame pressing the rear-cover sufficiently back, as shown in dotted lines in Fig. 2, until the frame arrives at the front-part of the casing and the ears of the frame are taken up by the notches of the front guide-arms and held in inclined position, as shown in Figs. 2 and 4. When the picture-frame is in this position, the pictures in the same can be inspected, while the pictures inserted in the rear-side of the foremost picture-frame on the guide-ways are exhibited below the same. The lever-arms d are then moved back into their rearmost position so as to take up the next picture-frame f which, when brought over the top, produces the tilting of the picture-frame then in inclined position on the guide-arms b so that the latter is tilted over the guide-arms, and placed by its ears on the guideways f on the side-walls, sliding backward thereon. One picture-frame after the other is thus carried

over the top-part of the casing for exhibition and tilted by the next following frame so as to be placed on the guide-ways and returned over the same toward the rear of the casing. During the taking up of the picture-frames by the lever-arms, the rear-cover is pressed back sufficiently so as to permit the picture-frames to be moved over the top of the casing, the rear cover following, so to say, the motion of the picture-frame, and closing again after the picture is brought over to the front-part of the casing, against the side-walls of the casing, so as to keep the rear-part of the casing closed and prevent the inspection of the pictures from the rear of the casing.

The exhibitor can be used on a smaller scale for photographs, picture-postcards, and the like and on a larger scale for advertising purposes in connection with larger sized pictorial or other advertisements, in which case motion may be imparted to the lever-arms by a spring, electric or other motor in connection with suitable actuating mechanism.

An application for a patent for my improved picture-exhibitor was originally filed on April 2, 1909, Serial No. 487,432, this present application being a continuation of said prior application.

Having thus described my invention, I claim as new and desire to secure by Letters Patent:

1. A picture exhibitor consisting of a casing, open at the front and rear and having a curved top, inclined ways having bent up front ends each having a notch therein, a plurality of picture-frames having, at the upper corners, projecting ears guided in said ways, and means for engaging the ears of the rearmost of said frames, and swinging the frame over the top of the casing, until said ears engage in said notches, whereby said frame is held upon said top in position to be viewed.

2. A picture-exhibitor consisting of a casing open at the front and rear and having a curved top, inclined ways at the upper part of said casing, said inclined ways having bent-up and notched front guide-rods and stop-arms at the rear-ends, a plurality of picture-frames provided with projecting ears at their upper corners and guided on said ways, and pivoted lever-arms having inwardly-bent rear-ends and take-up hooks adapted to loosely engage the ears on said frames and swing them in upward direction over and into engagement with said top and into reversed position with one edge resting in the notches of the guide-rods at the upper front-part of the casing.

3. A picture-exhibitor consisting of a casing open at the front and rear and having a curved top, inclined ways at the upper part of said casing, said inclined ways having

- bent-up and notched front guide-rods and stop-arms at the rear-ends, a plurality of picture-frames provided with projecting ears at their upper corners and guided on 5 said ways, pivoted lever-arms having inwardly-bent rear-ends and take-up hooks adapted to loosely engage the ears on said frames, and means for swinging said lever-arms and picture-frames in upward direction 10 over the top of the casing for moving said picture-frames over and into engagement with said curved top and bringing them into reversed position with one edge resting in the notches of the guide-rods at 15 the upper front-part of the casing and for tilting said frames from their upper position in downward direction so as to return them to the inclined ways.
4. A picture-exhibitor consisting of a casing 20 open at the front and rear and having a curved top, inclined ways at the upper part of said casing, said inclined ways having bent-up and notched front guide-rods and stop-arms at the rear-ends, a plurality of 25 picture-frames provided with projecting ears at their upper corners and guided on said ways, pivoted lever-arms having inwardly-bent rear-ends and take-up hooks adapted to loosely engage the ears on said 30 frames, and means for swinging said lever-arms in upward direction over the top of the casing to move the picture-frames over and into contact with said curved top and bring them into reversed position with one edge resting in the notches of the guide-rods at 35 the upper front-part of the casing.
5. In a picture-exhibitor, the combination, with a casing open at the front and rear, of pivoted lever-arms having inwardly-bent ends, means for swinging said lever-arms in 40 forward and backward position and a spring-actuated rear-cover hinged to the base of the casing and provided with means for being engaged by the rear-ends of said lever-arms so as to move the rear-cover into 45 open position and permit the automatic closing of the same on the actuation of the lever-rods.
6. In a picture-exhibitor, the combination, with a casing open at the front and rear, picture-frames in said casing, of pivoted lever-arms having inwardly-bent rear-ends, means 50 for swinging said lever-arms in forward or backward direction, and a hinged and spring-actuated rear-cover provided with 55 outwardly-bent lugs at its upper end adapted to be engaged by the rear-ends of the lever-arms for moving the rear-cover in backward position during the swinging of the picture-frames by the lever-arms over 60 the top of the casing.

In testimony, that I claim the foregoing as my invention, I have signed my name in presence of two subscribing witnesses.

AUGUST M. BECKER.
